DESIGN FOR A DENTAL APPARATUS HAND- PIECE OR THE LIKE

Adolph Hunau, Los Angeles, Calif.

Application January 12, 1946, Serial No. 125,525

Term of patent 7 years

(Cl. D24—1)

To all whom it may concern:

Be it known that I, Adolph Hunau, a citizen of the United States, residing at 458 No. Laurel Ave., Los Angeles 36, in the county of Los Angeles and State of California, have invented a new, original, and ornamental Design for a Dental Apparatus Hand-Piece or the like, of which the following is a specification, reference being had to the accompanying drawing, forming part thereof.

Fig. 1 is a side elevational view of a dental apparatus hand-piece or the like showing my new design.

Figs. 2 and 3 are end views as seen from the left and right, respectively, of Fig. 1.

I claim:

The ornamental design for a dental apparatus hand-piece or the like, substantially as shown.

ADOLPH HUNAU.
